United States Patent Office

Des. 180,422
Patented June 4, 1957

180,422

BOX

Allan Robinson, Boston, Mass.

Application July 9, 1956, Serial No. 42,177

Term of patent 3½ years

(Cl. D58—12)

Fig. 1

Fig. 2

I claim:

The ornamental design for a box, as shown and described.
